UNITED STATES PATENT OFFICE.

CHARLES H. COLLINS, OF AMSTERDAM, NEW YORK.

YARN-TUBE UNIT.

Application filed October 10, 1923. Serial No. 667,630.

To all whom it may concern:

Be it known that I, CHARLES H. COLLINS, a citizen of the United States, residing at Amsterdam, in the county of Montgomery and State of New York, have invented certain new and useful Improvements in Yarn-Tube Units, of which the following is a specification.

This invention relates to tube frames such as are used on Axminster looms, and the object of this invention is to improve the form, construction, and method of attaching the yarn tubes to the tube carrying angle of a modern tube bar.

15 The tube frames used on Axminster looms comprise frame-carrying chain engaging mechanism mounted on the ends of a tube bar, which bar also has mounted thereon the usual tuft yarn spools and yarn tubes.

20 On some of the older types of Axminster looms which utilize tube frames for inserting the tuft yarns between the warp yarns, each individual yarn tube is fastened to the tube bar proper. In the more modern types

25 of tube frames the individual yarn tubes are fastened to an angular strip of metal and the strip then fastened in place on the tube bar. This method permits of the handling of a large number of yarn tubes as a single 30 unit and so expedites the attaching of the yarn tubes to the tube bar, and is especially advantageous when attaching tubes to the latest types of tube bars which are of metal, or wood and metal.

35 My present invention lies in the method of attaching the yarn tubes to, and in the construction of, the angular strip of metal which is the tube carrying angle of a modern tube bar, and is clearly illustrated in the 40 accompanying drawings, in which:

Fig. 1 is an end view of a section of my improved tube carrying angle with yarn tubes in place thereon, a portion of a tube bar and of a tuft yarn being indicated by 45 dotted lines.

Fig. 2 is a front, and Fig. 3 is a rear view of a portion of a tube carrying angle with a number of yarn tubes in place thereon.

The same reference characters refer to the 50 same parts throughout the several views.

Referring to the drawings, A, A, represent 55 yarn tubes, and B the tube carrying angle piece. C indicates the tube bar of a tube frame, and D a tuft yarn in place in a yarn tube.

My improved tube carrying angle B, is

made from sheet metal of suitable gauge, the free end b^1 , of the horizontal flange thereof being preferably turned back into itself so as to form a smooth edge and at the same time 60 assist in stiffening the angle as a whole. At the free end b^2 , of the vertical flange of the angle B, I make a double bend, substantially as illustrated, so as to form a thickened edging or bead on the outside face of the flange. 65 This edging is of additional importance as it not only strengthens the angle as a whole but protects the tuft yarns by preventing their being drawn into contact with the upper edge of the yarn tubes, and provides a convenient stop and gauge against which to align the yarn tubes when assembling tubes and angle into a unit.

The vertical flange of the angle B is also provided with one or more rows of perforations b^3 , which perforations form an important part of this invention as they are a necessary part of my improved method or process of attaching the yarn tubes to the tube carrying angle. These perforations 70 make possible a very great saving in the time required to assemble a number of yarn tubes and a tube carrying angle into a single unit, by simplifying the secure and accurate attachment of the tubes onto the angle. With 75 my improved angle, to make such an attachment it is only necessary to place the requisite number of yarn tubes A, in a suitable holding and spacing jig or fixture, place the angle B thereon with the bead b^2 thereof 80 up against the upper end of the tubes, apply a suitable flux, and solder the parts together so as to form a unit.

As the application of the flux and the solder may be made by floating them through 85 the perforations b^3 , it requires much less time and heat to produce a secure and satisfactory union between the parts, and so reduces to a very appreciable extent the cost of producing such units. It also assures a more uniform 100 product, both in form and strength.

What I claim as my invention and desire to secure by Letters Patent is:

1. A yarn tube unit comprising a metal angle having a bead formed along the free 105 edge of one flange thereof by making a double bend therein said bead projecting beyond the face of said flange; a series of perforations through said flange and a plurality of metal yarn tubes the upper part thereof soldered to the face of said flange below said 110 bead.

2. A yarn tube unit comprising a metal angle having a series of perforations through one flange thereof, and a plurality of yarn tubes the upper part thereof soldered to the 5 face of the perforated flange of said angle.
3. A yarn tube unit comprising a metal angle having a bead formed along the free edge of one flange thereof said bead projecting beyond the face of said flange; a series of 10 perforations through said flange and below said bead; and a plurality of yarn tubes soldered to the face of said flange below said bead.
4. In a yarn tube carrying angle, a strip of 15 comparatively thin sheet metal shaped into an angle, one flange of said angle having a

series of spaced perforations formed therein whereby the necessary flux and solder may be introduced through said flange so as to attach the yarn tubes thereto. 20

5. A method of attaching metal yarn tubes to a metal tube carrying angle, consisting of forming a series of spaced perforations through one flange of said angle, placing the 25 yarn tubes under said perforations and substantially in contact with said flange, applying a suitable flux, and flowing melted solder into and through said perforations.

In testimony whereof I have affixed my signature.

CHARLES H. COLLINS.
